Inventor

Philip S. Stocker

By Clarence O'Brien, Attorney

UNITED STATES PATENT OFFICE

PHILIP J. STOCKER, OF JORDAN, MINNESOTA

ATTACHMENT FOR BRACES

Application filed January 3, 1930. Serial No. 418,378.

This invention relates to attachment for braces and an object of the invention is to provide means whereby a brace can operate in corners, narrow places and other restricted areas where the sweep of the ordinary brace would not permit its use.

Another feature of the invention is to provide an attachment that is adaptable for receiving screw driving attachments, socket wrenches or bits and to furthermore provide an attachment that can be used upside down or sidewise as desired.

A further object of the invention is to provide, in a manner as hereinafter set forth, a device of the character referred to that is strong, compact and durable, thoroughly reliable in its operation, very efficient for its intended purpose, very simple in its method of assembly, and comparatively inexpensive to manufacture and operate.

With the foregoing and other objects in view the invention consists of a novel construction, combination and arrangement of parts which will be hereinafter more specifically described and illustrated in the accompanying drawings, wherein is disclosed an embodiment of the invention, but it is to be understood that changes, variations and modifications may be resorted to without departing from the spirit of the claim hereunto appended.

In the drawings, wherein like reference characters denote corresponding parts throughout the several views:

Figure 1 is a front elevation of the brace in accordance with the present invention,

Figure 2 is a side elevation thereof,

Figure 3 is a vertical detailed sectional view taken substantially on the line 3-3 of Figure 1,

Figure 4 is an inner face view of the cover plate,

Figure 5 is a fragmentary plan view of the casing,

Figure 6 is a vertical sectional view in detail of the gripping attachment for screw drivers, bits or the like.

Referring to the drawings in detail, 7 indicates generally the brace which includes an elongated shank 8 merging at its upper end

in the crank arm 9 and the crank arm in turn merging with an upstanding handle 10. On the free end of the handle 10 is the customary knob 11 while rotatably supported on the crank 9 is a sleeve 12.

Supported on the lower end of the shank 8, in a manner presently to be described, is a circular casing indicated at 13 formed in the center with a circular depression or pocket 14. Surrounding the pocket 14 is an upstanding side wall 15 and on the outer face of the side wall 15 there is provided a plurality of radially extending notches 16. The casing is formed with an open top and a solid inner wall 17 the latter of which merges with the upstanding side walls 15.

The inner wall 17 is formed with a slot 18 that communicates with the pocket 14. On the outer face of the inner wall 17 there is formed an enlarged boss 19 provided with a horizontally extending opening 20 that communicates with the pocket 14 to provide a bearing for the spindle to be presently described.

The boss 19 is further provided with a recess or cavity 21 which opens into the slot 18 and extends at right angles to the opening 20 for the purpose of forming a bearing for the lower end of the shank 8. Projecting vertically from the casing 13 and formed integral therewith is a tubular sleeve 22 slotted intermediate its ends as at 23.

Projecting laterally from the upper end of the sleeve 22 is a handle 24 to be used in steadying the brace while it is being used.

The cover plate is indicated generally at 25 and is substantially a flat plate in the configuration of a horse-shoe formed on the inner face at the margin with an inwardly directed pin 26 that is adapted to detachably seat in any of the series of grooves 16.

From the center, of the inner face of the plate 25 there is formed an inwardly projecting spindle 27 that extends through the opening 20 and has the outer end thereof reduced and threaded as at 28. A washer 29 is disposed about the reduced end 28 of the spindle, and is held in tight abutment with the face of the boss 19 by a wing nut 30 that engages with the threaded end 28.

Adjacent the spindle 27 the cover plate is formed with an elongated slot 31 that communicates with the pocket 14 of the casing 13. The cover plate is held in detachable relation by screwing the wing nut 30 on the spindle 27. There is a circular opening 32 in the cover plate that extends from the slot 31 through its lower edge. The top wall of slot 31 is provided with a circular recess or cavity 33.

Rotatably mounted through the opening 32 and bearing in the recess 33 is a stub shaft 34 that extends through the slot 31. Rigidly secured to the upper end of the stub shaft 34 is a beveled gear 35 that is seated in the slot 31 and projects into the pocket 14. Rotatably mounted on the spindle 27 within the pocket 14 is a double faced miter gear 36 one face of which engages the stub shaft gear 35. The other face of the miter gear 36 engages with a beveled gear 37 that is rigidly secured to the lower end of the shank 8 and the gear 37 is seated in the slot 18. The lower end of the stub shaft 34 is preferably of a square configuration on one face of which is a spring pressed ball plunger 38 that is adapted to engage in a semi-spherical recess 39 formed in one side face of the socket 40 of any of the attachments.

As shown in Figure 3 of the drawings there is attached to the lower end of the stub shaft 34 a socket wrench attachment indicated generally at 41 provided with the customary nut socket 42 of any desired configuration. A bit or screw driver attachment for the stub shaft 34 is shown in Figure 6 of the drawings. The screw driving attachment shown in Figure 6 of the drawings includes a shank 43 of circular cross section and peripherally threaded as at 44.

At the upper end of the shank 43 is formed a socket 45 similar in all respects to the socket 40 shown in Figure 3 of the drawings in connection with the socket wrench attachment. The lower portion of the shank 43 is formed with a slot 46 within which is pivoted the upper ends of a pair of gripping jaws 47, 48 on a pin 49 that extends across the slot 46 and is anchored to the side walls thereof.

An internally threaded sleeve 50 is movable up and down the threaded portion 44 of the shank whereby the gripping jaws 47, 48 are moved inwardly to grip the square head of the shank of a screw driver.

Opposite the stub shaft 34, the cover plate is formed with a lengthwise extending threaded, circular cavity 51 in which is seated a screw 52 which when projected can be used for exerting pressure on the drill by causing the outer end of the screw to engage a rigid support.

From the foregoing description it will be apparent that the stub shaft 34 may be adjusted to any position about the casing 13 by loosening the wing nut 30 to permit the cover

plate 25 and its associated parts to be turned to the desired position. The pin 26 will then seat in another groove 15 after the nut is tightened.

Moreover since the casing 15 is disposed to one side of the shank 8 this offset portion provides for a sweep of the crank 9 without binding against any projecting surface.

It is to be understood that by describing in detail herein, any particular form, structure or arrangement it is not intended to limit the invention beyond the terms of the claim or the requirements of the prior art.

Having thus described my invention, what I claim as new is:

An attachment for a brace comprising in combination, a casing including an inner wall, outstanding side walls and an open outer face, said casing further formed with a projecting sleeve, for rotatably receiving the shank of a brace, a cover plate disposed over said open face of the casing and provided with an inwardly directed pin, the edge of said side walls provided with notches for selectively seating the pin, a spindle formed on the inner face of the cover plate and detachably secured to the inner wall of the casing, a stub shaft journaled in the cover plate, and means on the brace shank interconnected with means on the spindle and said stub shaft for turning the latter when the brace is turned.

In testimony whereof I affix my signature.

PHILIP J. STOCKER.
